UNITED STATES PATENT OFFICE.

WILLIAM MACDONALD, OF NEW WESTMINSTER, BRITISH COLUMBIA, CANADA.

LIFE-SAVING DRESS.

1,048,555.

Specification of Letters Patent. Patented Dec. 31, 1912.

Application filed August 1, 1912. Serial No. 712,614.

To all whom it may concern:

Be it known that I, WILLIAM MACDONALD, citizen of the United States of America, residing at New Westminster, in the Province of British Columbia, Canada, have invented a new and useful Life-Saving Dress, of which the following is a specification.

This invention relates to a life saving dress which has been designed to afford to the wearer both buoyancy and protection against cold when immersed in the water.

The invention comprises the combination with a body enveloping dress of water-proof material, of a secondary portion of water and air proof material attached to the upper part of the body enveloping dress with which it is in connection, and having provision by which it may closely encircle the neck of the wearer.

The main or body portion of the dress is of ample size that it may be worn over the ordinary clothes of the wearer, the object being that the air displaced from the body portion when the wearer is in the water, will collect in the supplementary air containing chamber formed by the secondary portion and will afford sufficient buoyancy to sustain the wearer in the water for a considerable length of time.

This dress being worn over the ordinary clothes of the wearer will, unlike a life belt, prevent the wearer from being directly exposed to the water and will enable the natural warmth of the body to be retained until such time as rescue is effected.

The invention is particularly described in the following specification, reference being made to the drawings by which it is accompanied, in which:

Figure 1 represents the general form of the dress, and Fig. 2, the upper part of it in part section showing the supplementary air retaining compartment formed around the shoulders when the lower part of the dress is immersed.

In these drawings 2 represents a body enveloping dress of water-proof material having legs and arms and cut sufficiently full, to enable a person of either sex to get readily into it with their clothes on, the only close fitting portion being that for the reception of the hand, which may either be fingered as a glove or formed as a mitt. The material of which this is made may be of stout fabric, such as is used for waders, but should be entirely water-proof. Its

ample fullness is not only designed to enable it to be worn over the ordinary clothes but is advantageous in that it includes a larger volume of air within it.

60

This garment is open at the upper end 3 above the shoulders and may be provided with a draw string to close it around the lower part of the neck but this tying need not be exceptionally close. Secured along the line 4 to the upper part of the body garment 2 about the level of the shoulders is a portion 5 of water-proof and air-proof material forming a neck closure and supplementary air container. This portion 70 5 is provided along its upper edge 6 with a neck band and draw string that it may be drawn close around the neck of the wearer and made practically water and air-tight. This portion of the dress should be made 75 of thin, light material that it may more easily be drawn closely around the neck.

As the neck closure 3 of the main body dress 2 is not drawn tight around the neck, the air displaced from the body envelop by the pressure of the water on the flexible material of it when the wearer is using it is driven into the supplementary air compartment 5, which is made full that it may be inflated by this air and will afford sufficient buoyancy to sustain the wearer for a considerable time. Not only is the wearer thus safely sustained in the water by the buoyancy of the inclosed air but he is not exposed to direct contact with the water 90 and the body and its ordinary clothes being entirely enveloped by the water-proof covering 2, the natural heat of the body is retained by the clothing. The person wearing the dress is thus enabled to endure the 95 exposure for a very much longer time than would otherwise be the case until rescued.

Having now particularly described my invention, I hereby declare that what I claim as new and desire to be protected in by 100 Letters Patent, is:

1. A life saving dress, comprising a portion enveloping the body up as far as the neck or shoulders and a supplementary portion attached to the upper part of the body 105 portion and in communication with the interior thereof, said supplementary portion having an upper edge that may closely encircle the neck.

2. A life saving dress, comprising a body 110 inclosing portion of flexible water-proof fabric enveloping the entire body up to the

neck or shoulders and a supplementary portion of water-proof material secured below the upper edge of the body portion and having an upper edge that may be drawn closely around the neck.

3. A life saving dress, comprising a body inclosing portion of flexible water-proof fabric conforming fully to the limbs and having an inlet aperture closable with a draw string around the base of the neck and a secondary envelop secured to the fore-

going about the level of the shoulders and having a draw string for closing around the neck above that of the main body envelop.

In testimony whereof I have signed my name to this specification in the presence of two subscribing witnesses.

WILLIAM MACDONALD.
